(57) **CLAIM**

The ornamental design for a charger for food thermometer as shown and described.

DESCRIPTION

FIG. 1 is a perspective view of a charger for food thermometer showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view thereof, showing the charger for food thermometer being used for charging a food thermometer.

The broken line showing of a food thermometer is included for the purpose of illustrating the charger for food thermometer in a configuration of use and forms no part of the claimed design.

1 Claim, 8 Drawing Sheets
